(57) **CLAIM**

The ornamental design for a portable housing, as shown and described.

DESCRIPTION

FIG. 1 is a front view of the portable housing showing our new design thereof;

FIG. 2 is a back side view thereof;

FIG. 3 is a bottom view thereof;

FIG. 4 is a left side view thereof;

FIG. 5 is a right side view thereof; and,

FIG. 6 is a top plan view of the interior view thereof. The broken lines depict portions of the portable housing that form no part of the claimed design.
